UNITED STATES PATENT OFFICE

90,966

DESIGN FOR A SUPPORT FOR FLOWER POTS

Rolland S. Bach, Cincinnati, Ohio

Application March 9, 1933. Serial No. 47,421

Term of patent 3½ years

To all whom it may concern:

Be it known that I, ROLLAND S. BACH, a citizen of the United States, residing at Cincinnati, in the county of Hamilton and State of Ohio, have invented a new, original, and ornamental Design for a Support for Flower Pots, of which the following is a specification, reference being had to the accompanying drawing, forming part thereof.

The figure is an isometric view of a support for flower pots, showing my new design.

I claim:

The ornamental design for a support for flower pots, substantially as shown.

ROLLAND S. BACH.
